(57) CLAIM

The ornamental design for a convertible crib, as shown and described.

DESCRIPTION

FIG. 1 is a perspective view of a convertible crib showing my new design;

FIG. 2 is a front view of the convertible crib of FIG. 1;

FIG. 3 is a rear view of the convertible crib of FIG. 1;

FIG. 4 is a right side view of the convertible crib of FIG. 1;

FIG. 5 is a left side view of the convertible crib of FIG. 1;

FIG. 6 is a top view of the convertible crib of FIG. 1; and,

FIG. 7 is a bottom view of the convertible crib of FIG. 1.

The broken line showing of a mattress is for illustrating environmental structure and forms no part of the claimed design. The uneven broken line representations in FIGS. 1-7 are for illustrative purposes only and form no part of the claimed design.
